UNITED STATES PATENT OFFICE.

EDWARD J. STECKLE, OF DIXON, ILLINOIS.

PNEUMATIC SEPARATOR FOR PULVERIZING-MILLS.

1,246,344.

Specification of Letters Patent. Patented Nov. 13, 1917.

Application filed January 31, 1916. Serial No. 75,418.

To all whom it may concern:

Be it known that I, EDWARD J. STECKLE, a citizen of the United States, residing at Dixon, in the county of Lee and State of Illinois, have invented a new and useful 5 Pneumatic Separator for Pulverizing-Mills, of which the following is a specification.

The present invention relates to an attachment for pulverizing mills for separating the fine material from the coarser particles, and has for an object to provide a device which effects this separation by pneumatic means, and which utilizes the pneumatic means for positively returning the 10 larger or coarser particles to the pulverizing mill to be reground.

Another object of this invention is to provide an apparatus which is of such form and construction that the material delivered 20 from the crushing or pulverizing mill is divided into a number of different streams, and is delivered in horizontal films or sheets, which are given a rotary spiral motion, and a draft of air is passed upwardly through 25 the film to lift therefrom the lighter particles, and allow the heavier or coarser particles to drop down into the bottom of a chamber. In carrying out this object of the invention, provision is also made for 30 preventing the return of the particles to the throat or passage leading from the pulverizing mill, so that at no stage of operation is it possible to choke the mill or any part of the apparatus.

35 A further object of the present invention is to provide a pneumatic circuit leading from the delivery side or part of the mill, which is preferably of the rotary hammer type, as will be hereinafter described and 40 as is shown in the accompanying drawings, and to return this air current to the mill at substantially the central portion thereof, so that the suction action of the mill serves as an auxiliary inducer to force the continu- 45 ous draft through the circuit.

A still further object of the invention is to provide a catch chamber to receive the coarser particles which are too heavy for the suction or air current to lift, and to connect 50 the bottom of the chamber with discharge pipes connecting with the return pipe of the air circuit, so that the suction in the return pipe effects a positive feeding of the coarser particles from the chamber back 55 into the central portion of the pulverizer, so that the material may be reground.

There are various other equally important objects and advantages of this invention, which will be more clearly brought out in the following description of the present preferred embodiment of this invention, the same being illustrated in the accompanying drawings, wherein—

Figure 1 is a front elevation of a pulverizing machine of the rotary hammer type, 60 having the improved pneumatic separator attachment applied thereto.

Figure 2 is a side elevation of the same, parts of the device being shown in section.

Figure 3 is a horizontal sectional view, enlarged, taken on the line 3—3 of Fig. 2, and showing the interior of the separating chamber and the delivery nozzles in the lower part thereof.

Referring to these drawings, 10 designates 75 the casing or body portion of a pulverizing or grinding mill, shown in the present instance as being of the hammer type, and having the rotary head 11, provided with radiating hammer arms 12, cooperating with 80 grinding plates 13, to pulverize or crush the material, which is fed into the mill, through the hopper 14. The head 11 is mounted on a transversely extending shaft 15 on one end of which is arranged a balance or fly wheel 85 16, while the opposite end is provided with a belt receiving pulley 17, by means of which the pulverizing mill is adapted to be turned. As shown to advantage in Fig. 2, the mill is provided at its top, and at one side of the 90 central shaft 15, with an upwardly extending throat or outlet passage 18, through which the material crushed is delivered by centrifugal force, and by the air current produced by the rapid rotation of the head 11 95 and the hammers 12. The material is thus thrown upwardly through the throat 18 by centrifugal force. The throat 18 is provided with a plurality of baffles 19, which are in the form of longitudinally spaced 100 apart slats, extending transversely in the throat 18, and being pivoted at their opposite ends in the sides of the throat. The slats or baffles 19 are adapted to be turned into horizontal position, and to overlap more 105 or less to open and close the throat to the desired extent, and to thus control the size of the crushed material which passes out of the casing of the mill 10. If the material is too large to pass between the baffles 19, 110 it is deflected backwardly into the casing and taken up by the hammers 12, so that

the material is carried back into the machine and is further ground. However, the baffles 19 are not sufficient to correctly and accurately gage the size of the particles and deliver the same at a constant or uniform size.

The top of the throat 18 is provided with an uptake chamber 20, the bottom of which preferably tapers, as shown to advantage in Figs. 1 and 2, and is provided with a 10 pair of horizontal diametrically extending inverted V-shaped receivers 21, which intersect centrally of the casing to divide the bottom of the same into four compartments, which flare upwardly, so as to provide 15 positively inclined sides to receive material dropped into the bottom of the uptake chamber 20, and direct the same to the relatively small bottoms in the several compartments. The material passing the baffles is 20 forced upwardly into the receivers 21, and is delivered therefrom through a plurality of nozzles 22, which project from one side of each receiver 21, and extend circularly and in the same direction, and which also 25 project upwardly at a slight angle, as shown in Figs. 2 and 3.

Fitting into the top of the uptake chamber 20 is a suction pipe 23, which leads into the intake of a fan 24, the same being 30 mounted upon a suitable frame 25, placed in the upper end of a collecting hopper 26, and delivering thereto at one side of the hopper to produce a cyclone separator, wherein the particles taken up by the current of air from the uptake chamber are 35 permitted to fall into the bottom of the relatively large hopper 26, while the air which is delivered in a spiral current to the top of the hopper is drawn off through the return 40 pipe 27. It will be noted from Fig. 2 particularly, that the end of the return pipe emerging from the top of the hopper 26 is relatively large, as at 28, while the diameter, or cross sectional area, of the pipe 27 decreases gradually from the end 28 to the 45 mill 10, to which the current of air is returned. In order to equalize the pressure of the air at the opposite sides of the mill, the return pipe 27 is branched, as at 29 to 50 provide two arms or portions, which extend downwardly at the opposite sides of the device, and which deliver into the opposite sides of the casing 10, as at 30, slightly above the shaft 15.

55 As before mentioned, the bottom of the uptake chamber 20 is divided into four parts or pockets, into which the heavier or coarser material is received. From the relatively small bottoms of these pockets or 60 compartments, discharge pipes 31 lead, the same extending downwardly and opening at their lower ends into the sides of the adjacent return branches 29 of the air circuit. The suction in the branches 29, which 65 is caused not only by the current of air

forced into the hopper 26, but also by the action of the hammers 12, creates a suction in the pipes 31, and draws outwardly therethrough the heavier particles from the compartments or pockets in the chamber 20. 70 The particles are thus drawn into the lower ends of the branches 29, and are forced into the casing 10, and are consequently reground. At a point in the pneumatic system, preferably in the top of the return or 75 pressure pipe 27, a vent 32 is provided, the same having therein a valve 33 to control the outlet of air forced through the pipe 27 from the hopper 26. As the fan 24 creates a suction upwardly through the pipe 23, 80 through the uptake chamber 20, and through the mill 10, the induced current of air thus produced may be regulated more or less by manipulating the valve 33 to control the passage of air therethrough to thus vary 85 the lifting power of the induced current and adjust the device to a nicety in the separation of the finer particles from the coarser ones.

The bottom of the collecting hopper 26 90 may be provided with a trough 34, in which a conveyer 35 is mounted so as to continuously feed the relatively fine selected material from the bottom of the hopper to any suitable point of discharge. 95

In the operation of the improved device, material is fed through hopper 14 into the casing 10, and is, in the usual manner, ground or pulverized to a certain extent and drawn upwardly into the throat 18. 100 The material is impinged against the baffles 19, and it will be noted that the baffles are arranged at such an angle that they provide a plurality of more or less restricted passages in the throat 18, so that material of a 105 predetermined size only is permitted to pass through the throat. The larger particles of the material are deflected back into the casing 10 and reground. The material, which passes upwardly through the throat 18, is 110 carried therethrough, not only by the air pressure from the revolving hammers 12, but also by reason of the induced draft produced by the action of the fan 24. The material is carried up into the radiating and 115 intersecting receivers 21, where it is drawn into the respective nozzles 22, and carried upwardly therethrough in a circular path and delivered substantially tangentially within the chamber 20, so that the material is 120 divided up into a plurality of streams, which are whirled in cyclonic fashion around the interior of the uptake casing 20. This action produces a plurality of spiral streams, which rise upwardly and gradually in the 125 casing, and which spread the material over a relatively large area to thus separate the material and admit of the easy lifting of the finer particles upwardly through the suction pipe 23. The heavier particles are more 130

at liberty to fall into the bottom of the chamber 20 by reason of this spreading out and dividing of the material. The disposition of the nozzles is such that the heavier particles cannot by gravity fall backwardly through the nozzles, but must drop on top of the receivers and be deflected by the oppositely inclined walls thereof into the bottoms of the various compartments. As the nozzles 22 are relatively small in diameter as compared with the cross sectional area of the receivers and of the chamber 20, the material is given increased impetus or velocity in passing through the nozzles, so that the suction through the nozzles is comparatively great and no chance is made possible of the blocking or clogging up of the nozzles. Furthermore, the restricted areas of the nozzles effect the expulsion of the material therefrom with comparatively great force, so that the material spreads outwardly from the ends of the nozzles and spreads into a relatively broad spiral stream. The induced current holds the finer particles in suspension and draws the same upwardly from the chamber 20, but allows the gradual fall of the heavier particles from the whirling stream to thus effect the gradual and positive separation of the different grades of the material.

From the uptake chamber 20, the material is carried through the section 23 and fan 24, into the hopper 26. It is delivered in the hopper at one side thereof and substantially tangentially thereto, so that a whirling or spiral stream of air and material is produced. As the hopper 26 is relatively large, the force of the air suction or pressure is lost, and the material is permitted to drop into the bottom of the hopper, while the air is caused to pass upwardly through the relatively large end 28 of the return or pressure pipe 27. The air passes through the pipe 27, and through the branches 29 into the opposite sides of the casing 10, so as to return the air substantially to the central portion of the rotary part of the mill, to thus take advantage of the suction created at the central portion of the mill, as the hammers 12 are revolved. This inward flow of air through the pipes 29 into the casing 10 creates a suction in the pipes 31, which communicate with the lower end of the chamber 20, so that the heavier particles of material which fall into the bottom of the chamber and are deflected into the pipes 31, are positively drawn by the air current down into the inner ends or bottoms of the branches 29 and forced into the casing 10 of the mill, and into the path of the rotary hammers 12. It is thus observed that not only is a thorough separation of the pulverized material effected, but also the material which has not been ground or pulverized to the desired state is positively returned to

the mill to be recrushed, and the positive means of returning this material to be recrushed is also utilized in separating the particles.

It will thus be readily understood that a very efficient, economical, and practical device is provided for separating the material and adjusting the device to produce a finished article of the desired fineness, and also that the material which is rejected by the separator is positively returned to the mill, without the provision of exterior or secondary means.

This whirling or circular motion of the material which issues from the nozzles 22 is produced by the impact of the material against the inner cylindrical wall of the uptake chamber 20, which chamber is, as shown in Fig. 3, cylindrical in cross section, whereby the material which is delivered from the nozzles at substantially a tangent to the chamber is directed in a curved path and at the same time is drawn upwardly by the suction of the induced current, so that a whirling spiral action is imparted to the material in the chamber 20. The chamber 20 may be provided with any number of pockets or compartments in the bottom, and any number of nozzles, which are sufficient to receive, and to eject the material and permit the choking of the device.

It is, of course, understood that it is within the spirit of the invention to modify and change the above specifically set forth structure, as far as is permissible within the scope of the following claims.

What is claimed is:—

1. The combination with a rotary pulverizing mill, provided at the top with an upwardly extending throat through which the material is delivered by centrifugal force, of an uptake chamber having a closed bottom, said bottom serving as a top for the throat, a nozzle communicating with the throat through the bottom and extending upwardly above the bottom to deliver the ground material tangentially within the chamber, means for drawing off the light particles of ground material from the top of the chamber, and means for returning the coarse particles of material from the bottom of the chamber to the mill.

2. The combination with a rotary pulverizing mill, of an uptake chamber having a closed bottom formed with a plurality of compartments, means for delivering the ground material from the mill against the underside of said bottom, a plurality of nozzles corresponding in number to the compartments and opening through said bottom and extending upwardly therefrom to deliver the ground material from beneath the bottom into the chamber over said compartments, means for drawing off the light particles of the ground material from the top

of said chamber, and means for returning the heavy particles from said compartments in the bottom of the chamber to the mill.

3. The combination with a pulverizing mill, of a separating chamber having a throat communicating with said mill and with an outlet pipe at its upper end, nozzles communicating with said throat and extending upwardly and circumferentially into said separating chamber, means for creating a draft through said pulverizing mill and separating chamber, and means at the bottom of said separating chamber to allow the heavier particles of the material to pass through.

4. The combination with a pulverizing mill, of a separating chamber having a plurality of compartments in its lower end which have closed bottoms, and means for feeding a separate stream of ground material from the mill upwardly through each compartment, means for carrying off the lighter particles of the material from the upper end of the chamber, and means for returning the heavier particles from the compartments to the mill.

5. The combination with a pulverizing mill, of a chamber, nozzles communicating with the outlet of the mill and extending spirally upward into the chamber for conveying the ground material from the mill to the interior of the chamber in a plurality of separate spiral streams, means for creating a current of air upwardly through said chamber and said streams of material to carry off the lighter particles, and permit the heavier particles to fall onto the bottom of the chamber, and pneumatic means for returning the heavier particles to the mill.

6. The combination with a pulverizing mill, of a chamber communicating with the outlet thereof and being circular in cross section, means for creating an up draft through said chamber, a spirally extending nozzle rising from the bottom of the chamber and extending toward the side thereof and delivering substantially at a tangent against the interior cylindrical wall of the chamber to deliver the material from the mill tangentially against the circular wall and thus impart a whirling action to the issuing stream of material.

7. The combination with a pulverizing mill, of a separating chamber having a plurality of compartments in its lower end, each compartment having an inclined wall, nozzles projecting upwardly from the inclined walls into the chamber and communicating at their lower ends with the outlet of said mill to project ground material from the mill upwardly into the chamber, the coarse particles of the material being adapted to fall on said inclined walls, and return pipes leading from the lower

ends of the walls to the mill to return the coarse material thereto.

8. The combination with a pulverizing mill, a separating chamber communicating therewith, a plurality of receivers in the bottom of said chamber adapted to receive the material from the mill, a plurality of nozzles extending spirally upward from the receivers and terminating adjacent the inner wall of the chamber and having their outlets extending in one circular direction, and means for creating an up draft through the chamber to force the material from the receivers through said nozzles, whereby the material is adapted to issue in a plurality of circularly directed streams and break up into a relatively broad film within the chamber.

9. The combination with a pulverizing mill, of a separating chamber having a plurality of compartments in the lower end thereof, each compartment having an inclined wall, nozzles extending through the inclined walls and communicating at their lower ends with the outlet of said mill and having their upper ends projecting spirally upward into the chamber above said inclined walls, means for creating a suction upwardly through the chamber to feed the material from the mill and deliver it into the chamber in a plurality of separate spiral streams, and means at the lower ends of said inclined walls to carry the coarser material dropping from the spiral streams back to the mill to be reground.

10. The combination with a pulverizing mill, of a chamber having a tapered chamber projecting upwardly into the chamber, nozzles communicating with the outlet of the mill and projecting spirally and upwardly from the sides of the said bottom into the chamber, means for feeding ground material from the mill upwardly through said nozzles into the chamber, the coarser material being adapted to fall back upon said tapered bottom, means for carrying off the finer material from the chamber, and means for returning the coarser material from said bottom to the mill.

11. The combination with a pulverizing mill having an upwardly opening discharge throat, of a chamber connected to the throat, an inclined bottom in the chamber constituting a top for the throat, means for forcing the ground material upwardly through the throat against the top thereof, a nozzle extending upwardly from the top to carry off the material impinged thereagainst, said nozzle extending spirally upward in the chamber and delivering the material tangentially against the side thereof and at a point above the upper end of the bottom to admit the free flow of the material and the dropping of the heavy particles thereof on the inclined bottom, whereby the said particles

at liberty to fall into the bottom of the chamber 20 by reason of this spreading out and dividing of the material. The disposition of the nozzles is such that the heavier particles cannot by gravity fall backwardly through the nozzles, but must drop on top of the receivers and be deflected by the oppositely inclined walls thereof into the bottoms of the various compartments. As the nozzles 22 are relatively small in diameter as compared with the cross sectional area of the receivers and of the chamber 20, the material is given increased impetus or velocity in passing through the nozzles, so that the suction through the nozzles is comparatively great and no chance is made possible of the blocking or clogging up of the nozzles. Furthermore, the restricted areas of the nozzles effect the expulsion of the material therefrom with comparatively great force, so that the material spreads outwardly from the ends of the nozzles and spreads into a relatively broad spiral stream. The induced current holds the finer particles in suspension and draws the same upwardly from the chamber 20, but allows the gradual fall of the heavier particles from the whirling stream to thus effect the gradual and positive separation of the different grades of the material.

From the uptake chamber 20, the material is carried through the section 23 and fan 24, into the hopper 26. It is delivered in the hopper at one side thereof and substantially tangentially thereto, so that a whirling or spiral stream of air and material is produced. As the hopper 26 is relatively large, the force of the air suction or pressure is lost, and the material is permitted to drop into the bottom of the hopper, while the air is caused to pass upwardly through the relatively large end 28 of the return or pressure pipe 27. The air passes through the pipe 27, and through the branches 29 into the opposite sides of the casing 10, so as to return the air substantially to the central portion of the rotary part of the mill, to thus take advantage of the suction created at the central portion of the mill, as the hammers 12 are revolved. This inward flow of air through the pipes 29 into the casing 10 creates a suction in the pipes 31, which communicate with the lower end of the chamber 20, so that the heavier particles of material which fall into the bottom of the chamber and are deflected into the pipes 31, are positively drawn by the air current down into the inner ends or bottoms of the branches 29 and forced into the casing 10 of the mill, and into the path of the rotary hammers 12. It is thus observed that not only is a thorough separation of the pulverized material effected, but also the material which has not been ground or pulverized to the desired state is positively returned to

the mill to be recrushed, and the positive means of returning this material to be recrushed is also utilized in separating the particles.

It will thus be readily understood that a very efficient, economical, and practical device is provided for separating the material and adjusting the device to produce a finished article of the desired fineness, and also that the material which is rejected by the separator is positively returned to the mill, without the provision of exterior or secondary means.

This whirling or circular motion of the material which issues from the nozzles 22 is produced by the impact of the material against the inner cylindrical wall of the uptake chamber 20, which chamber is, as shown in Fig. 3, cylindrical in cross section, whereby the material which is delivered from the nozzles at substantially a tangent to the chamber is directed in a curved path and at the same time is drawn upwardly by the suction of the induced current, so that a whirling spiral action is imparted to the material in the chamber 20. The chamber 20 may be provided with any number of pockets or compartments in the bottom, and any number of nozzles, which are sufficient to receive, and to eject the material and permit the choking of the device.

It is, of course, understood that it is within the spirit of the invention to modify and change the above specifically set forth structure, as far as is permissible within the scope of the following claims.

What is claimed is:—

1. The combination with a rotary pulverizing mill, provided at the top with an upwardly extending throat through which the material is delivered by centrifugal force, of an uptake chamber having a closed bottom, said bottom serving as a top for the throat, a nozzle communicating with the throat through the bottom and extending upwardly above the bottom to deliver the ground material tangentially within the chamber, means for drawing off the light particles of ground material from the top of the chamber, and means for returning the coarse particles of material from the bottom of the chamber to the mill.

2. The combination with a rotary pulverizing mill, of an uptake chamber having a closed bottom formed with a plurality of compartments, means for delivering the ground material from the mill against the underside of said bottom, a plurality of nozzles corresponding in number to the compartments and opening through said bottom and extending upwardly therefrom to deliver the ground material from beneath the bottom into the chamber over said compartments, means for drawing off the light particles of the ground material from the top

of said chamber, and means for returning the heavy particles from said compartments in the bottom of the chamber to the mill.

3. The combination with a pulverizing mill, of a separating chamber having a throat communicating with said mill and with an outlet pipe at its upper end, nozzles communicating with said throat and extending upwardly and circumferentially into said separating chamber, means for creating a draft through said pulverizing mill and separating chamber, and means at the bottom of said separating chamber to allow the heavier particles of the material to pass through.

4. The combination with a pulverizing mill, of a separating chamber having a plurality of compartments in its lower end which have closed bottoms, and means for feeding a separate stream of ground material from the mill upwardly through each compartment, means for carrying off the lighter particles of the material from the upper end of the chamber, and means for returning the heavier particles from the compartments to the mill.

5. The combination with a pulverizing mill, of a chamber, nozzles communicating with the outlet of the mill and extending spirally upward into the chamber for conveying the ground material from the mill to the interior of the chamber in a plurality of separate spiral streams, means for creating a current of air upwardly through said chamber and said streams of material to carry off the lighter particles, and permit the heavier particles to fall onto the bottom of the chamber, and pneumatic means for returning the heavier particles to the mill.

6. The combination with a pulverizing mill, of a chamber communicating with the outlet thereof and being circular in cross section, means for creating an up draft through said chamber, a spirally extending nozzle rising from the bottom of the chamber and extending toward the side thereof and delivering substantially at a tangent against the interior cylindrical wall of the chamber to deliver the material from the mill tangentially against the circular wall and thus impart a whirling action to the issuing stream of material.

7. The combination with a pulverizing mill, of a separating chamber having a plurality of compartments in its lower end, each compartment having an inclined wall, nozzles projecting upwardly from the inclined walls into the chamber and communicating at their lower ends with the outlet of said mill to project ground material from the mill upwardly into the chamber, the coarse particles of the material being adapted to fall on said inclined walls, and return pipes leading from the lower

ends of the walls to the mill to return the coarse material thereto.

8. The combination with a pulverizing mill, a separating chamber communicating therewith, a plurality of receivers in the bottom of said chamber adapted to receive the material from the mill, a plurality of nozzles extending spirally upward from the receivers and terminating adjacent the inner wall of the chamber and having their outlets extending in one circular direction, and means for creating an up draft through the chamber to force the material from the receivers through said nozzles, whereby the material is adapted to issue in a plurality of circularly directed streams and break up into a relatively broad film within the chamber.

9. The combination with a pulverizing mill, of a separating chamber having a plurality of compartments in the lower end thereof, each compartment having an inclined wall, nozzles extending through the inclined walls and communicating at their lower ends with the outlet of said mill and having their upper ends projecting spirally upward into the chamber above said inclined walls, means for creating a suction upwardly through the chamber to feed the material from the mill and deliver it into the chamber in a plurality of separate spiral streams, and means at the lower ends of said inclined walls to carry the coarser material dropping from the spiral streams back to the mill to be reground.

10. The combination with a pulverizing mill, of a chamber having a tapered chamber projecting upwardly into the chamber, nozzles communicating with the outlet of the mill and projecting spirally and upwardly from the sides of the said bottom into the chamber, means for feeding ground material from the mill upwardly through said nozzles into the chamber, the coarser material being adapted to fall back upon said tapered bottom, means for carrying off the finer material from the chamber, and means for returning the coarser material from said bottom to the mill.

11. The combination with a pulverizing mill having an upwardly opening discharge throat, of a chamber connected to the throat, an inclined bottom in the chamber constituting a top for the throat, means for forcing the ground material upwardly through the throat against the top thereof, a nozzle extending upwardly from the top to carry off the material impinged thereagainst, said nozzle extending spirally upward in the chamber and delivering the material tangentially against the side thereof and at a point above the upper end of the bottom to admit the free flow of the material and the dropping of the heavy particles thereof on the inclined bottom, whereby the said particles

fall downwardly over the bottom, and discharging means at the lower end of the bottom to receive the heavy particles and return the same to the mill to be reground.

5 12. The combination with a pulverizing mill having an upwardly opening throat, of a separating chamber connected to the top of the throat, means for inducing an air current upwardly through the throat and the 10 chamber whereby to lift the pulverized material from the mill to the chamber, an inclined bottom in the chamber at the top of the throat to check the upward flow of the material, a nozzle opening at one end 15 through the bottom to receive the material therethrough, the nozzle opening at its opposite end above the inclined bottom and adjacent and at a tangent to the wall of the chamber whereby to deliver the material upwardly through the chamber in a spiral stream, the heavy particles being adapted to drop on said inclined bottom and move downwardly thereover, and discharging means at the lower end of the bottom for 20 receiving the heavy particles and returning the same to the mill.

13. The combination with a pulverizing mill having an upwardly opening throat, of a chamber at the upper end of the throat, a 30 bottom in the chamber comprising a plurality of inclined walls in the top of the throat, means for feeding material up through the throat from the mill and against said walls, nozzles leading from the walls to receive the 35 material thrown thereagainst, the nozzles extending spirally upward in the chamber and opening adjacent the wall thereof and above the upper ends of the inclined walls to deliver the material in cyclonic fashion into 40 the chamber, the heavier particles being adapted to fall on the bottom and move downwardly over the inclined walls, and discharge pipes opening at the lower ends of the walls to receive the heavier particles and 45 return the same to the mill.

14. The combination with a pulverizing mill having an upwardly opening throat, of a chamber at the upper end of the throat, a bottom in the chamber comprising radially 50 extending inverted V-shaped walls presenting oppositely inclined sides at their upper faces and presenting converging lower sides at the top of the throat, means for feeding the ground material upwardly through the 55 throat against said V-shaped walls, a nozzle carried at one side of each V-shaped wall and extending laterally and upwardly at

substantially right angles thereto for the reception of the material impinged against the lower faces of the walls, said nozzles extending upwardly and outwardly to a point above the upper edges of the walls and adjacent the inner wall of the chamber to deliver the material at substantially a tangent against the inner wall of the chamber and above the bottom whereby the material may freely issue from the nozzles and the heavier particles may fall upon the bottom and move downwardly in opposite directions over the inclined faces of the inverted V-shaped walls thereof, and discharge pipes opening at the lower ends of said walls to receive the downwardly moving material and leading to the inlet of said mill to return the heavier particles thereto. 75

15. The combination with a pulverizing mill having an upwardly opening discharge throat, of a chamber connected to the throat, an inclined wall between the chamber and the throat, means for feeding ground material upwardly through the throat and against said inclined wall, a nozzle opening through the wall and extending into the chamber above the wall to receive the material impinged against the wall and deliver 85 the same into the chamber, the heavier particles dropping on said inclined wall and falling downwardly thereover, and returning means leading from the bottom of the wall to the inlet of said mill and adapted to 90 receive the falling particles and return the same to the mill to be reground.

16. A dust separator comprising a casing having discharge means for the tailings located at the lower end thereof, an outlet for 95 the fines leading from the upper portion thereof, an inlet conduit for the dust-laden air leading into the lower portion of said casing, elbow pipes arranged on the upper end of said inlet conduit within the casing, 100 said elbow pipes having their free end portions curved and terminating above the discharge means for the tailings and inclined upwardly and laterally whereby the tailings are first thrown upwardly and tangentially 105 against the vertical walls of the casing.

In testimony that I claim the foregoing as my own, I have hereto affixed my signature in the presence of two witnesses.

EDWARD J. STECKLE.
